UNITED STATES PATENT OFFICE.

MICHAEL QUINLAN, OF BRISTOL, VERMONT, ASSIGNOR TO NEW HAVEN MILLS
MANUFACTURING COMPANY, OF NEW HAVEN MILLS, VERMONT.

BOX-FORMING MACHINE.

1,101,038.

Specification of Letters Patent. Patented June 23, 1914.

Application filed July 8, 1912. Serial No. 708,287.

To all whom it may concern:

Be it known that I, MICHAEL QUINLAN, citizen of the United States, residing at Bristol, in the county of Addison and State 5 of Vermont, have invented certain new and useful Improvements in Box-Forming Machines, of which the following is a specification.

My invention relates to box making machinery, and particularly to machines for 10 making very small wooden boxes having notched interlocking ends.

One object of my invention is to provide a box making machine of the character 15 above referred to which is relatively simple in construction, positive in its operation and which will automatically assemble boxes having a very small cubical content.

Another object is to so construct the box 20 making machinery that it is adjustable within certain limits so that boxes of various sizes may be made in the same machine.

A further object is to provide means 25 whereby glue may be applied to the tongued ends of the boxes prior to their being moved into position to engage the box sides.

Another object is to provide a machine 30 in which either the sides and ends may be assembled without the bottom, or the box assembled with the bottom as desired.

A further object is to provide a mechanism of the character described wherein provision is made for automatically feeding the end blanks and side blanks into position, 35 automatically feeding if desired the bottom into position, automatically applying glue to the tongued ends of the end blocks, automatically forcing the ends and sides into engagement with each other, and automatically discharging the completed box.

An embodiment of my invention is illustrated in the accompanying drawings wherein:

Figure 1 is a side elevation of my improved box making machine. Fig. 2 is a vertical section on the line 2—2 of Fig. 1. Fig. 3 is a plan view partly in section. Fig. 4 is a view partly in section and partly in elevation of the glue applying mechanism, 45 this view being a section taken on line 4—4 of Fig. 2. Fig. 5 is a fragmentary section on line 5—5 of Fig. 2. Fig. 6 is a fragmentary perspective view of one end of the machine showing one of the end blank hoppers, the glue applying mechanism, the feed-

ing device for the end blanks and the hammer for forcing the ends into engagement with the sides. Fig. 7 is a section on the line 7—7 of Fig 1. Fig. 8 is a perspective view of the slide for operating the abutment 60 carrying slide and its operating mechanism. Fig. 9 is a perspective view of the side blank hoppers and the feeding means therefor, this view also showing the means for feeding the bottoms into position. Fig. 10 is a 65 fragmentary section on line 10—10 of Fig. 1. Fig. 11 is a perspective view of the abutment, a portion of the device for feeding the box bottom to the assembling space and the means for feeding end blanks to the assembling space. Fig. 12 is a perspective view of the ejector and the guideway through which the boxes are ejected.

Corresponding and like parts are referred to in the following description and indicated 75 in all the views of the accompanying drawings by the same reference characters.

Referring to Figs. 1, 2 and 3, 2 designates a bed mounted upon supporting legs, this bed being of open or skeleton formation. 80 The bed is provided with a glue trough 3 which is sunk below the level of the bed and is kept warm in any suitable manner.

Disposed upon a slide 4 mounted in guides 15 on the bed at one side of the glue trough 85 is one end blank hopper designated 5 and including the parallel spaced side walls 6 and 6^a. One of these walls 6^a is fixed while the other, 6, is shiftable to adjust it toward or from the opposite wall 6^a. To this end, 90 the wall 6 has a base flange 7 which is transversely slotted at a plurality of points as at 8, and into these slots pass screws or bolts 9. By loosening these screws, it is obvious that the wall 6 may be shifted toward or 95 away from the wall 6^a and that by tightening the screws, the wall may be held in its adjusted position. The hopper 5 is open at one end and at the other end is closed by an end piece 10 through which passes a 100 feed plunger 11. It will be noted that the end piece 10 is sufficiently long to close the end of the hopper for any adjustment of the wall 6. The plunger 11 passes through a yoke 12. Contractile springs or like devices 13 are connected to the end of the plunger and at their inner ends are attached to any fixed support as for instance the pins 14 projecting from the side walls of the hopper 5 as shown most clearly in Fig. 6. Sup- 110

ported between the side walls of the hopper are the end blanks A. The bed 2 is formed with lateral undercut guides 15 between which the slide 4 slides so as to be 5 adjustable to thereby accommodate boxes of greater or less length. It will be understood, of course, that the glue trough 3 is of a length equal to that of the largest box made by the machine.

10 Disposed upon the opposite margin of the glue trough or pan 3 is the end blank hopper 16, composed of the spaced side walls 17 and 17^a. This hopper is constructed in precisely the same manner as the hopper 5 but 15 need not be adjustable toward or away from the hopper 5, though it may be so made. The wall 17 is, however, adjustable toward or from the wall 17^a, it being provided to this end with the base flange formed with 20 slots 18 through which pass screws 19. The end of the hopper is closed by an end piece 20 and carrying a yoke 21 and through this yoke passes a feeding plunger 22 which presses against the end blanks A'. The 25 plunger is forced inward by means of the contractile springs 23 attached to projecting pins 24.

Extending outwardly from the hopper 5 is a vertical wall 25 upon which is mounted 30 the oppositely disposed horizontally arranged guides 26 forming a guideway between which the feeding plunger of the end blank hopper 5 moves.

Preferably and as illustrated, the guides 35 26 are mounted upon and formed integral with a plate 27, and preferably and in order to vertically adjust the guideway formed by the plate 27 and the guides 26, the vertical wall 25 is vertically slotted as at 28, and 40 screws or bolts 29 pass through these slots. As illustrated in Fig. 6, the face of the wall 25 is cut out so as to form a recess 30 within which the guide plate 27 shifts. By forming the wall 25 with the recess 30, the feed plunger or push rod may always be supported so 45 as to engage the middle of the end blank, no matter what its height may be. Slidably mounted between the guides 26 and in said guideway is a reciprocating feed plunger 31 50 or push rod which is illustrated particularly well in Fig. 6. This feed plunger carries at its extremity a spring finger 32 which is attached to the face of the plunger and extends slightly outward or away from the 55 face of the guideway and is provided with inwardly projecting terminal ears 33. When the feed plunger 31 is moved toward the hopper 5, these terminal ears which are rounded at their edges ride up over the first 60 end blank of the series contained within the hopper 5 so that the terminal ears press against the middle of the block and at the same time the inner end of the plunger 31 engages the edge of the first end block of the 65 series and as the plunger reciprocates, this

end block is shifted over as shown in Fig. 3 in dotted lines to the position where the box is to be formed.

As illustrated in Fig. 6, the wall 25 at its inner end is upwardly extended as at 34, and 70 immediately above the opening of the hopper 5 there is disposed an outwardly projecting hub 35 which is formed with a vertical guideway 36. Disposed in this guideway is an angular finger 37. The body of this finger is longitudinally slotted while the lower end thereof is angularly bent as at 38, this angularly bent end striking the first block of the series slightly above its middle as 75 illustrated in Fig. 4. A screw 39 passes 80 through the slot in the finger and extends into the hub 35 so that the finger as a whole may be vertically adjusted with relation to the opening of the hopper 5.

Projecting from the plate 37 below the 85 slot thereof is a screw 40, and mounted upon this screw is an angular plate or finger 41 which is vertically slotted for the passage of the screw 40 and, which has an inwardly extending terminal end which engages the 90 face of the block A below its middle. It will thus be seen that the first block A of the 95 series of end blocks or blanks contained within the hopper 5 is forced into contact with the angular terminal ends of the fingers 37 and 41, as illustrated in Fig. 4, and that the end blanks A are held firmly between the plunger 31 and these angular terminal ends of the fingers. These fingers do not project in so far as to interfere with the 100 movement of the plunger 31 and the spring finger 32 passes between the angular terminal ends of the members 37 and 41.

The base upon which the hopper 5 and the wall 25 are mounted is formed with a 105 ledge or track designated 42 which extends across the front of the hopper with its upper edge in line with the bottom of the hopper, and this ledge as shown in Fig. 6 supports the end blank from the time it is forced into 110 engagement with the angular ends of the members 37 and 41 until it is forced into position to form the box as will be hereafter described.

Mounted upon the flange 7 is a guide for 115 the end blank, preferably made of wire. This guide comprises a looped base 43 through which a set screw 9^a passes. The base then extends upward, then toward the front of the hopper, then outward parallel 120 to the line of travel of the end blank, then upward and downward in the form of an arch as at 44 (see Fig. 6) toward the glue trough as at 45, the extremity being outwardly inclined so as to readily receive the 125 end blank and to guide the same in its course past the space between the inner wall 6 of the hopper and the hammer 46 to be later described.

Mounted upon the hammer 46 is a guid- 130

ing spring 47. The hammer 46 is provided with the upwardly projecting post 48, and projecting through this post is a screw or bolt 49. The spring finger 47 is angular in form and the upper end thereof is vertically slotted to receive the bolt 49. The lower end of this slotted portion extends downward to a level with the upper edge of the end blank A and is then flattened and downwardly bowed as at 50 so as to press gently upon the upper edge of the end blank as it travels from the mouth of the hopper to the position shown in Fig. 6. During all this period, the spring finger 32 holds the blank in position, and when the blank reaches the position shown in Fig. 6, the spring finger 32 holds it firmly against the end of the hammer block 46. When it has reached the position shown in Fig. 6, the end blank is in position to be assembled with the side blanks as will be later described.

The mechanism for feeding the end blanks from the hopper 16 is precisely the same as that described for the hopper 5. Projecting upwardly from the bed is a vertical wall 51 which corresponds to the vertical wall 25 previously described, and mounted upon this wall is the guideway 52 which is precisely the same construction as the guideway 27 previously described. Sliding laterally in this guideway is the plunger rod 53 which acts to urge the blanks contained within the hopper 16 into position where they may be assembled with the side blanks. This plunger rod like the plunger rod 31 is provided with the spring finger 54 and having the inwardly turned ears 55.

The wall 51 is upwardly extending as at 56 and is formed with the central thickened hub 57 corresponding to the hub 35. This hub is formed with a vertical guideway in which is adjustably disposed the finger 58, being held in place by the screw 59. The lower end of this finger is angularly bent as at 60, and mounted upon the finger 58 is an angular finger 61 corresponding to the finger 41 previously described. The end blanks A' are held in position between the plunger 22 and the spring fingers and in position so as to be engaged by the inner end of the plunger rod 53 as the latter slides across the face of the hopper 16. The blank is supported upon a projecting ledge 56 corresponding to the ledge 42 and the blank 55 is guided by means of the arched guide 57 which corresponds in every particular with the arched guide 44.

It will be noted from Fig. 3 that while the hoppers for the end blanks are similar in construction and the actuating mechanism therefor is the same for both hoppers, yet the position of the hoppers is different and that the hopper 16, for instance, is set nearer to the side of the machine than the hopper 5 and that the glue trough 3 is offset at one

end. The reason for thus placing the hoppers out of alignment with each other is that the end blanks A' are to be applied last of all while the end blanks A are the first blanks to be moved into position.

Both the end blanks A and A' are formed with tongues so as to interengage with tongues upon the side blanks B and B'. It is desirable that the inner faces of the end blanks, and particularly the inner faces of the tongues, be wiped with glue or like adhesive before they are moved into position, and to this end I have provided glue applying mechanism which is shown particularly in Figs. 4 and 6. Both of these glue applying mechanisms are alike and a description of one will suffice for the other. Taking, therefore, the glue applying mechanism for the hopper 6, it will be seen that projecting upward from the enlargement 34 of the wall 25 there is a grooved standard forming a guide and designated 62. Mounted in this vertical guide 62 is a reciprocating slide rod 63 having projecting from it an apertured lug 64 through which passes a transverse shaft 65. Mounted upon the ends of the shaft are the sleeves 66 having downwardly and outwardly projecting socketed arms 67. Extending downward from these arms are the wires 68 forming extensions of the arms. These wires extend downward and outward for a distance and then extend vertically downward and at their ends carry glue brushes 69 which normally dip into the glue trough 3 and which are so spaced apart that when the slide 63 is raised, the glue brushes wipe against the side margins of the blank A. It will be seen that the sleeves 66 may be laterally adjusted upon the shaft 65 so as to space the glue brushes apart from each other the required distance for any sized end blanks within the limits of the machine, and further it will be seen that the wires 68 are supported in sockets 67 and are adjustable in these sockets by means of set screws. The means for reciprocating the sliding rod 63 will be later described together with means for reciprocating the plungers for feeding the end blanks from their hoppers.

The box is formed in line with the hammer 46 as illustrated in Fig. 3 and disposed on one side of the space C within which the box is formed is a sliding abutment 70, the particular function and construction of which will be later described. Opposed to the abutment 70 are certain guides which will also be later described, the two sides B and B' of the box (see Fig. 3) being shoved into place between these guide stops and the abutments. Extending from one end of the machine to the space C within which the box is formed, is a guideway designated 71. This guideway is formed by laterally disposed walls 72 and 73 (see Fig. 10) which are formed with longitudinally

extending dovetailed grooves 74 upon the inner faces. The lower faces of these walls 72 and 73 are rabbeted as at 75. The wall 72 is fixed relative to the bed of the machine 5 but the wall 73 is laterally adjustable, this wall being provided with outwardly projecting slotted lugs 76 as illustrated in Fig. 9 through which pass binding screws 77. The guideway is thus adjustable so as to 10 accommodate it to various widths of boxes. The walls 72 and 73 are mounted upon a sliding plate 78 and this plate in turn is slidingly mounted upon the bed 4. This bed 4 is slotted as at 79 for the passage of a feeding chain for the bottoms.

Disposed at the inner ends of the walls 72 and 73 are the hoppers 80 and 81 to receive the side blanks B and B'. These blanks are formed with tongues at their 20 ends. The blanks are arranged so as to extend parallel to the walls 72 and 73. The hoppers are formed each by the side walls 82 and 83. These side walls are angular in cross section. Each wall 82 is fixedly 25 mounted upon the slide plate 78 and each wall 83 is adjustably mounted, the base of the wall being laterally slotted as at 84 and having set screws 85 passing down through the slots. It will be noted from Fig. 9 that 30 there are two of these hoppers 80 and 81, and that they are arranged on each side of the guideway 71. The side blanks B and B' are fed into the guideway by means of plungers 86 which pass through guides 87. 35 The outer end of each plunger is connected by contractile springs 88 to eyes 89 carried by the side walls 82 and 83 so that the blanks contained within each hopper 80 or 81 are fed forward by the pressure of these contractile springs.

Engaging the grooved walls 72 and 73 of the track 71 are feed rods 90. Each rod has a dovetailed rib extending partly along its length which engages with the dovetailed 45 groove 72. These feed rods 90 are reciprocated by mechanism which will be hereafter described. When the feed rods move back so that the inner ends of the ribs align with the walls 82 of the hoppers 80 and 81, the 50 plungers 86 will force the side blanks into the guideway 71. Then as the feed rods 90 move inward, the ribs on the feed rods will engage the outer ends of these side blanks and push them inward along the 55 guideway and into position in the assembling space C. It will be understood that inasmuch as each feed rod 90 extends beyond the inner end of the rib, this projecting portion of the feed rod acts as a stop to prevent 60 the outward movement of the side blanks beyond the tracks upon which the side blanks move. The feed rods never move so far outward as to permit the ends of the feed rods beyond the ribs escaping the open 65 ends of the hoppers.

Passing along the slot 79 and a slot 79^a in the sliding plate 78 is a sprocket chain 91. This sprocket chain passes over sprocket wheels 92 and 93, the sprocket wheel 92 being mounted upon the outer end of the sliding plate 78 while the sprocket chain 93 is mounted at the inner end of the guideway as illustrated in dotted lines in Fig. 3. This sprocket chain carries projecting from it the paddles or studs 94. As illustrated there 70 are three of these paddles or studs adapted to engage with bottom blanks which are fed into the guideway between the reciprocating feed rods 90. The means for actuating the sprocket chain will be later described. 75

The two walls 82 and 83 forming the hopper 81 and the wall 73 of the guideway 71 are all mounted upon a sliding plate 95 adapted to slide laterally in guides 96 mounted upon the bed plate of the machine. 80 Extending parallel to the direction of movement of the feed rod or plunger 31 and attached to the bed of the machine is a guide strip 97 which also coacts with the guide strip 96 and disposed between these two 85 guide strips 96 and 97 is a slide 98 carrying upon it an upwardly extending adjustable wall 70. This wall 70 is adjustable laterally with relation to the slide 98, and to this end is mounted as shown in Fig. 11 in laterally extending guide strips 99 mounted upon the plate 98. These guide strips form a dovetailed slideway and the bottom of the member of the block 70 is formed with a dovetailed tongue 100 which engages in this 90 dovetailed slideway. This permits the block 70 to be slid laterally. The inner face of the block 70 is vertical and smooth faced, and when the slide 98 is in one position, the inner face of the block forms a wall against 95 which the side blank B' is carried. The block 70 is provided near its bottom and just above the guide strip 99 with a projecting ledge 101 adapted to support the side blank as the side blank is shifted into position. 100

On the opposite side of the assembling space C are arranged the adjustable supports 102, 103 and 104. The support 102 consists of a pin having an enlarged base, the enlarged base forming a shoulder. This 110 pin is shiftable into a plurality of perforations 105 formed in the bed of the machine. The support 103 projects upward and has near its base on its inside face a ledge 106 at the same height as the ledge formed on 115 the pin 102, and the support 104 is made in precisely the same manner as the support 103 and is formed with a ledge 107. These three ledges are intended to support one of the box sides as it is moved into position. 120 The pin 102 may be adjusted into one or the other of the perforations 105 to accommodate boxes of a larger or smaller size. The support 103 is upwardly extended as at 108 and passing therethrough is a clamp 125 130

screw which engages in the slotted body 109 of a finger having an angularly turned end 110, which is adapted to press down upon the top edge of the box side as it is shifted 5 into position. The block 70 is also provided with a finger for engaging the upper edge of the box side supported against the face of the block 70. To this end the block 70 is upwardly extended as at 111 and through 10 this extension passes a clamp screw 112. The finger 113 is horizontally disposed in the line of travel of the box side and is angularly bent and upwardly extended as at 114 and formed with a slot through which the 15 clamp screw 112 passes. It will be seen that these fingers may be adjusted up or down so as to press with greater or less force against the upper edges of the box sides.

Projecting from the end of the slide 98 20 is a box support comprising an outwardly projecting arm of wire designated 115 having an upwardly turned terminal end. This wire arm extends upward and outward. As 25 a means of limiting the inward movement of the slide 98, I form the bed plate with a series of perforations 116 (see Fig. 2) and provide a pin 117 which engages in any one of these perforations and forms a stop limiting the inward movement of the slide 98. 30 The slide 98 reciprocates within its guides and the means for moving this slide will be described later.

Disposed between the wall 83 of the hopper 80 and the support 103 is a sliding block 35 designated 118 and illustrated in Fig. 8 in detail. This sliding block is connected to a slide plate or strip 119 moving in guides mounted upon the bowed plate. This slide plate or strip 119 extends transversely of the 40 line of movement of the side blocks. The block 118 in its normal position is in alignment with the inner face of the support 103 but it may be shifted from this position to the position shown in Fig. 3 where the active 45 face of the block is in line with the inside face of the block 70 and closes the end of the box forming space C. This block 118 has a flat vertical face 120 against which the end block A' bears when the two end blanks and 50 the side blanks are placed in position. The block 118 carries upon it the upwardly projecting lug 121 carrying the angular finger 122 which is adapted to bear upon the end blank A' and support the end blank.

55 It will be noted that the side walls 82 and 83 terminate short of the slot in the plate 78 so that a ledge 123 is left over which the tongues 74 move, which ledges form tracks for the side pieces. Beyond the side wall 83 60 of the hopper 81 there is a guiding spring 125 (see Fig. 3), this being yieldable so as to permit the block 118 to shift into the position shown in Fig. 3. Normally the block 118 occupies a retracted position opposite

the spring 125 and spaced therefrom the 65 width of the passageway through which the side blanks travel.

The block 118 as illustrated in Fig. 8 is formed on its lower margin with a projecting ledge or track 126 to support the side blank as it is shifted toward the box forming or assembling space. This ledge 126 is formed by a strip received in a recess 127 on the under face of the block and resiliently forced outward by springs 128 as illustrated 70 in Fig. 8. The reason for making the strip 126 yielding is to permit the block 118 to be shifted up closely against the face of the block 70 in the position shown in Fig. 3. The slide 119 is connected in any suitable 75 manner to the operating mechanism as will be later described, and it may be merely stated here that the slide is provided with an upwardly projecting lug 129 which extends 80 up through a slot 130 formed in the sliding plate 95.

Assuming that the box is formed in the manner as will be described later, it is necessary that the complete box should be shifted 90 into such position that it may be discharged. It is for this reason that the plate 98 slides laterally carrying the completed box resting upon the ledge 111 and supported between this ledge 111 and the spring finger 113. The outwardly shifting block 95 70 carries the box with it until the box arrives opposite a discharge channel 131 (see Figs. 3 and 12). This discharge channel is 100 formed by two spaced walls 132 and 133 mounted upon the slide 4. The wall 133 is fixed on this sliding plate while the wall 132 is adjustable toward or from the wall 133 and to this end is formed with an angular slotted base through which pass clamp screws 134 as clearly illustrated in Fig. 12. 105 By this means the discharge channel may be narrowed or widened in order to suit various widths of boxes.

The plate 4 is adapted to be adjusted 110 toward or from the middle of the machine by means of an adjusting screw 135 passing through a lug 136 formed upon the table or bed, the adjusting screw being provided with a handle. Any suitable means, however, may be used for adjusting this slide 4 toward or from the center of the machine. It will be seen that the slide carries with it the hopper 5, the feeding means for said 115 hopper, the glue applying means therefor, the hammer 46 and the discharge channel 131. 120

The hammer 46 is illustrated in detail in Fig. 6. As shown in this figure, the plate 42 has laterally disposed guides thereon designated 137 and mounted in these guides is the hammer 46 which is provided at its base with the downwardly and outwardly projecting tongues 138. The guides 137 are connected at their rear ends as at 139 and 125

projecting upward therefrom is a lug 140 through which passes a stop pin 141 which limits the rearward movement of the hammer. The hammer has a sliding movement 5 toward and from the box assembling space.

Before describing the mechanism whereby the various movements necessary are secured, it may be well to describe the general operation of forming a box in accordance with my invention.

The hoppers 5 and 16 are filled with end blanks disposed as shown in Fig. 3 and the hoppers 80 and 81 are filled with side blanks disposed as shown in Fig. 9. The first movement of the machine is to shift the first end blank of the series from the hopper 5 laterally in the direction of the arrow in Fig. 3 to the end of the box forming space C where it is supported against the hammer and by 10 means of the finger 50 in the position shown in Fig. 6. At the same time that this is occurring, the push rods 90 are moving inward and the tongues on these rods engage the first side blanks B and B' of the series 15 and force them forward along the guideway 71. As these blanks are forced forward they come into position shown in Fig. 3, that is, on each side of the space C. As soon as 20 the side blanks have moved into the position shown in Fig. 3, the second end blank is shifted inward from the position immediately in front of the mouth of the hopper 16 to the position shown in Fig. 3 at the end of the box forming space. At the same time 25 that the end shifts over from the mouth of the hopper 16 to the end of the box forming space, the abutment block 118 also shifts and occupies the position shown in Fig. 3. The four pieces from which the box is formed are 30 now in position. If the bottom is not to be applied to the box at this time, the hammer is now forced home which forces the tongued end pieces into engagement with the 35 tongues at the ends of the side pieces and the box is completely formed. If the bottom is to be applied to the box, then before the 40 second end piece A' is shifted into the position shown in Fig. 3, the tappet 94 on the chain 1 moving along the guideway will 45 carry with it a box bottom D.

It will be understood that the hopper bottoms are to be fed by hand to the chain 91. In other words, the hopper bottoms are inserted one by one on the chain and carried 50 forward between the members 90, the members 90 therefore acting as guides. The tappet 94 of course engages the bottom and the bottom is gradually fed into position by the chain. I do not, of course, wish to be limited to feeding the box bottoms into place 55 by hand as automatic means might be used for this purpose.

After the box is completely formed and the hammer is operated so as to lock the 60 parts in their connected position, the block

70 slides over as before described so as to carry the box to the entrance of the delivery channel 131 and the box is swept out along the delivery channel as will be later described. As soon as this occurs, the slide 98 moves so as to carry the block 70 back to the position shown in Fig. 3 and at the same time the abutment 118 is carried back so that its face is in alignment with the face of the supporting members 103 and 104, thus 75 leaving the way clear for a new box to be fed.

Power is applied to the machine by means of a power shaft designated 142 as shown in Fig. 1, this shaft carrying upon it a power wheel to which power is applied by means of a belt or in any other suitable manner. The shaft extends longitudinally under the machine and in order to drive the endless sprocket chain 91, the shaft 142 is 80 provided near its extremity with a worm gear 143 which engages with a gear wheel 144 carried upon a shaft 145 which in turn supports the sprocket wheel 92. Thus a continuous rotation in one direction is communicated to the sprocket wheel 92 and from the sprocket wheel 92, of course, to the sprocket wheel 93.

Projecting upward from the tables are the upwardly extending brackets or standards 146 and 147 journaled in which is the shaft 148 which constitutes the shaft whereby nearly all of the motions communicated to various parts of the machine are secured. This shaft 148 as seen in Fig. 6 carries upon 95 it the eccentric 149 over which passes an eccentric band 150. Projecting downward from this band is the eccentric rod 151 which is offset at its lower end and has a vertically slotted head 152 disposed immediately over the slot in the rear end of the hammer 46.

Pivots mounted upon a fixed support 153 is one link 154 of a toggle. The end of this link 154 is longitudinally slotted. Pivotally mounted in the bifurcated rear end of the hammer 46 is a link 155, the upper end of this link being perforated for the passage of a bolt 156 which passes through the slot in the end of the arm 154, passes through the perforation in the end of the arm 155 and into the slot in the head 152. By means of the longitudinal slot in the head 152, the amount of throw of the hammer 46 may be adjusted. By means of the stop 141 the rearward movement of the hammer may be limited. It will be seen that upon a rotation of the shaft 148 a reciprocating motion will be given to the hammer block 146 so as to throw it backward and forward toward and from the track or guideway over which the end blank A passes. The shaft 148 carries upon it a crank 157 as shown in Figs 1, 2 and 6.

Mounted upon the upper end of the stand- 130

ard 146 is a laterally extending bracket 158 formed in two sections adjustable upon each other so as to shorten or lengthen the bracket. The bracket extends at right angles to the shaft 148 and then extends longitudinally parallel to the shaft 148 for a distance slightly beyond the position of the eccentrics 149 as at 159. The bracket as this point is formed with a bearing for the end of shaft 164 extending longitudinally parallel to said shaft and projecting from the base of section 159 is an arm 160 formed at its end with a slotted head 161 constituting a support for a sliding rod 176. The bracket 158 is preferably made in two sections, one of the sections being formed with slots 162 while the other section has set screws 163 passing through said slots so that the bracket section 159 may be adjusted. The extremity of the section portion 159 of the bracket 158 as before stated, carries a bearing to support the end of shaft 164. This shaft extends longitudinally and parallel to shaft 148. Mounted upon this shaft 164 is a lever 165 formed in two sections, one end of one of the sections being formed with a slotted yoke 166. The crank pin 167 of the crank 157 passes through the slot of this yoke. It will be obvious, therefore, that as the shaft 148 is rotated, the crank will cause a rocking movement of the lever 165. As before stated, this lever is made in two sections, one of said sections being formed with a slot 168 while the other section is provided with a pin 169 which passes through the slot and holds the lever 165 in any adjusted position. This lever 165 is connected by means of a link 170 to the upper end of the reciprocating bar 63. It will therefore be obvious that as the lever 165 is reciprocated, the bar 63 will be reciprocated and thus the glue wipers or brushes 69 will be wiped against the tongued ends of the end pieces A. This shaft 164 also carries upon it the crank 171 whose crank pin engages in a slotted yoke 172 formed on the end of a like lever 173 pivotally mounted upon the shaft 164. This lever 172 is connected by means of a link 174 to the upper end of the reciprocating bar 63 which reciprocates the glue brushes or wipers for the hopper A'.

Mounted upon the shaft 148 is a cam 175 for actuating the pushers which feed the end blanks A out of the hopper 6. Mounted upon the extremity of the arm 161 is a sliding rod 176 which slides through an opening in the end of the arm 161 and which carries at its inner end a roller 177 which engages with the face of the cam 175. The other end of the rod is pivotally connected to a lever 178 which extends downward and outward and is formed at its lower end with a slotted yoke 179 which engages over a screw pin 180 projecting from the plunger 31 (see

Fig. 2). This lever 178 is formed in two sections, one of said sections being slotted as at 181 and the other section being provided with adjusting screws 182 which engage in said slots so that the lever may be adjusted for length. The rod 176 is also formed in two parts, one of said parts being slotted as at 183 while the other part is provided with a pin 184 whereby the rod may be held in its lengthened or shortened condition. 70

It will be seen that the rotation of the shaft 148 will cause a rotation of the cam 175 and that this in turn will wipe against the roller 177 and cause the rod 176 to reciprocate, thus oscillating the lever 178 and reciprocating the sliding plunger 31, thus feeding the end blanks A one by one into position at the end of the box forming space C. 75

The mechanism for operating the sliding plunger 53 is the same as that for the plunger 31. The standard 185 is provided with the arm 186 which is provided with a slotted head 187 corresponding to the slotted head at the end of the arm 160. Mounted upon the shaft 148 is a cam 189 which wipes against a roller carried upon the end of a rod 190 which rod is pivotally connected to a lever 191 corresponding in every respect to the lever 178 which at its lower end is pivotally connected to the slide 53. The cams 175 and 189 are so set relatively to each other that the cam 175 operates before the cam 189 and thus the movement of the end blank A' is retarded behind the movement of the end blank A. 85

For the purpose of shifting the abutment 118, I provide a cam 192 mounted upon the shaft 148 and engaging with the bell crank lever 193 pivoted upon an adjustable bracket 194 projecting outward from the standard 185. This bracket 194 is vertically movable upon the standard 185. The bell crank lever at its upper end carries a roller 195 which bears against the cam 192 and the lower arm of the bell crank lever has a slotted yoke 196 which engages with a pin 197 projecting upward from the lug 129 upon the slide 119. It will be seen that as the shaft 148 rotates, the bell crank lever 110 will be oscillated and this in turn will give a reciprocation to the slide 119 and the abutment 118, the length of travel of the slide being sufficient to carry the abutment from the position shown in Fig. 3 to a position 115 where its inner face is in alignment with the working face of the support 103. 120

For the purpose of reciprocating the feed rods 90, I provide a cam 198 having a cam track 199 in its periphery. Mounted upon the standard 147 at the end of the machine is a bracket 200, this bracket carrying a transversely extending supporting member 201 upon which a lever 202 is pivoted. The upper end of this lever is formed with a lon- 125

itudinally slotted head 203, and mounted upon the bracket 200 is a lever 204, the inner arm of which is upwardly curved and then extended into engagement with the cam 5 groove 199. The other end of the arm as before stated projects into the slotted head 203 so that as the cam rotates, the lever 204 will be reciprocated and the lever 202 reciprocated. The lower end of the lever 202 10 is formed with a longitudinally slotted head 205 which engages with a plate 206 adjustably mounted upon the feed plungers or slide rods 90. This plate is rigidly attached to one of the slide bars but is transversely 15 slotted as at 207. Clamp screws 208 extend through these slots and into the opposite slide rod or plunger. It will thus be seen that one of the slide rods may be adjusted relatively to the other so as to accommodate 20 boxes of different widths within certain limits. The plate 206 is formed with an upwardly projecting lug 209 which has a pin 25 engaging in the slotted end of the lever 202. The means for shifting the wall 70 is as follows. Mounted upon the short longitudinal shaft 142 is a segment gear 211 which meshes with a rack bar 212. This rack bar is connected to the slide 98 as illustrated in 30 Fig. 2. The rack bar operates against the force of the spring 213. As the shaft rotates, the segment 211 will engage the rack, will shift the rack in one direction, and as soon as the segment gear releases its engagement with the rack, the spring 213 will 35 turn the parts to their original position. It will thus be seen that the block 70 will be reciprocated and shifted from the position shown in Fig. 3 to a position where the acting face of the block is parallel with the 40 wall 132 so as to permit the formed box to be laterally shifted into the discharge passage 131.

The means for shifting the box into the discharge passage and along the same is 45 illustrated in Figs. 1 and 12. Mounted upon the shaft 148 is a cam 214 formed with a cam track 215 in its face. Projecting out from the standard 146 is a bracket arm 216, and mounted upon a downwardly projecting member 217 extending from this bracket 50 is a lever 218. The upper end of this lever is formed with a slotted head 219, and mounted upon the extremity of the bracket arm 216 is a lever 220, one end of which 55 projects into the slot of the upper end of the arm 218 and the other end of the lever engages in the cam track 215. By this means it will be seen that as the shaft 148 is rotated, the lever 218 will be oscillated, and that the lower end of the lever will 60 swing in the direction of the discharge passage between the walls 132 and 133.

It will be noted from Fig. 1 that the lever 65 218 is not so long as to extend down very far into the passage when the lever is in its

normal position. When the lever is oscillated, however, the lower end, which is relatively wide as illustrated in Fig. 12, engages with the rear end of the box and the box is moved forward into the discharge passage. 70 It will be seen that each box as it is made is forced into this discharge passage and that the entire row of boxes contained between the walls 132 and 133 are shifted until the boxes drop out at the end of the passage. 75

The general operation of the invention is as follows. The shaft 148 is of course driven from the main driven shaft. As the shaft rotates, the crank 216 will first act to reciprocate the glue brushes so as to cover the 80 ends of the end blank A with glue. As soon as this has happened, the cam 175 will operate to actuate the lever 178 and push the end blank into the position shown in Fig. 6, that is, immediately opposite the end of the 85 space C where the box is formed and against the inner end of the hammer 46. Meanwhile, the cam 198 will operate to shift the lever 202 and shift the slide rods 90 longitudinally so that each slide rod will engage 90 one of the side blanks B and B' and shift them into position one against the block 70 and the other against the supports 102, 103 and 104. If the bottom of the box is to be put on, a bottom is fed to the endless chain 95 91 and the paddle 94 will engage the bottom, shift it longitudinally and slip it into place between the two side blanks, the edges of the bottom fitting the grooves in the side blanks. As soon as the sides and bottom are in place, the cam 189 operates to shift the end blank 100 A' across the machine and into the position shown in Fig. 3. The four sides of the box are now ready for assembling and as soon as this is accomplished, the eccentric 105 149 operates and the hammer 46 is driven quickly against the end of the box so that the box blanks are compressed between the hammer and the abutment 118 which is moved over with the end blank A'. This 110 stroke of the hammer is of great importance as it finally finishes the box and forces the parts into thoroughly close interlocking engagement. As soon as this has been accomplished, the block 70 shifts laterally by 115 reason of the engagement of the segment gear with the rack and inasmuch as the box is supported between the ledge 101 and the finger 113, the box will be carried outwardly with the blocks 70. When the block 120 70 reaches a position so that its inside flat face is parallel to the inner face of the wall 132, the cam 214 will actuate the ejector lever 218 which will force the box outward into the discharge passage. As soon as 125 this occurs, the member 70 will be shifted back into position, the button 118 will also move into its original position and the parts will be ready for the formation of a new box. 130

It is to be particularly noted that all the parts are adjustable within certain limits so that various sizes of small boxes may be readily made within certain limits.

5. What I claim is:

1. A box forming machine including a bed, laterally spaced members mounted upon said bed and defining the sides of a box assembling space, means for delivering an end blank into position at one end of said space, means acting subsequently for delivering side blanks into said space and between the laterally spaced members, means for delivering a second end blank into position at the end of said space opposite the first end blank, and means for forcing said side and end blanks into engagement with each other.

2. A box making machine including a bed, laterally spaced members mounted upon the bed and defining the sides of a box assembling space, means for delivering one end blank into position at one end of said space, means for delivering side blanks into said space and between the laterally spaced members, means for delivering a second end blank into position at the end of said space opposite the first end blank, means for applying glue to the margins of the end blanks, and means for forcing said blanks into engagement with each other.

3. A box making machine including in its organization a bed, laterally spaced members defining the sides of a box assembling space, end blank hoppers open at one end, glue applying means reciprocating past the open ends of the hoppers, means for delivering an end blank from one of said hoppers into position at one end of said space, means for delivering a pair of side blanks into position in said space and against the laterally spaced members, means for delivering an end blank from the other hopper into position at the end of said space opposite the first end blank, means for forcing said blanks into engagement with each other, and means for ejecting the box.

4. A box forming machine including a bed, laterally spaced members mounted on the bed defining the sides of a box assembling space, end blank hoppers, vertically reciprocating glue applying devices moving past the open ends of the hoppers, means for urging the end blanks contained within said hoppers toward the open mouths of the hoppers, horizontally disposed reciprocating delivering devices shiftable past the open mouths of the hoppers to deliver the end blanks therefrom and carry said end blanks to an assembling space, side blank hoppers arranged oppositely to each other, means urging the side blanks contained within said hoppers toward the open mouths of the hoppers, tracks leading to the said box assembling space, and horizontally dis-

posed reciprocating delivery devices disposed between said side blank hoppers and reciprocating to carry said side blanks into position between the end blanks in the assembling space.

5. A box forming machine including a bed, a glue trough disposed below the bed, oppositely disposed slides movable over the glue trough, hoppers for containing end blanks and disposed each upon one of said slides, means urging the end blanks in said hoppers toward the open ends of the hoppers, vertically reciprocating glue applying devices arranged one in connection with each hopper, horizontally reciprocating delivery rods, one mounted upon each slide and each movable past the open end of a corresponding hopper, laterally disposed supports defining an assembling space between said slides, a member defining one end of said assembling space and against which one of the end blanks is delivered, a guideway extending to the other end of said assembling space, side blank hoppers arranged one on each side of said guideway, means for urging the blanks contained within said hoppers one by one into said guideway, and horizontally disposed reciprocating means for feeding said blanks one by one along said guideway to the end of the assembling space.

6. A box forming machine including in its organization a bed, horizontally disposed opposed sliding members mounted upon said bed and movable toward and from each other, end blank hoppers arranged one upon each of said sliding members and having delivery openings facing each other, means for adjusting the distance between said slides, and means for delivering the end blanks from each of said hoppers to an assembling space.

7. In a box forming machine, a bed, opposed slides horizontally arranged upon said bed and adjustable toward and from each other, hoppers horizontally arranged and carried each upon one of said slides, said hoppers opening toward each other, means for urging end blanks contained within said hoppers toward the open mouths thereof, and reciprocating pusher rods moving past the mouths of the hoppers to deliver the end blanks therefrom to an assembling space.

8. A box forming machine including in its organization a bed, opposed horizontally arranged slides mounted upon the bed and movable toward and from each other, opposed end blank hoppers carried one upon each of the slides and opening toward each other, means urging the end blanks contained within said hoppers toward the open mouths thereof, vertically reciprocating glue applying devices movable past the open mouths of the hoppers, and horizontally re-

ciprocating feeding devices movable transversely to the axes of the hoppers and delivering the end blanks to an assembling space.

5 9. A box forming machine including in its organization a bed, a horizontally arranged hopper including side walls mounted upon said bed, one of said side walls being adjustable nearer to or farther from the 10 other side wall, the said hopper being adapted to support vertically arranged blanks, resilient means for urging said blanks toward the open mouth of the hopper, a supporting member extending transversely beyond the 15 open mouth of the hopper and forming a track, the upper edge of said supporting member being disposed flush with the bottom of the hopper, a laterally adjustable stop finger disposed immediately in front 20 of the hopper and holding the blanks with the first named blank of the series projecting from the mouth of the hopper and resting with its edge on said track, and laterally reciprocable means moving on said 25 track and engageable with said blank to shift it from in front of the hopper.

10. A box forming machine including in its organization a bed, a horizontally arranged blank hopper including opposite parallel walls, one of said walls being laterally adjustable, means resiliently urging the blanks toward the open mouth of the hopper, a track disposed beneath the open mouth of the hopper and extending transversely of the walls, the upper edge of the track being flush with the bottom of the hopper, a plurality of angular, relatively adjustable fingers disposed opposite the open mouth of the hopper, the ends of said fingers being 40 adapted to engage the first blank of the series supported within the hopper and hold it on the said track and prevent a farther outward movement thereof, and a reciprocating device mounted upon said track and reciprocating across the open mouth of the hopper and engageable with the first blank of the series to deliver the same.

11. In a box forming machine, a bed plate, a horizontally disposed hopper including 50 oppositely disposed side walls adjustable toward or from each other, a spring actuated plunger mounted in said hopper and adapted to engage the last blank of a series of vertically supported blanks in said hopper 55 and urge said blanks toward the mouth of the hopper, a track extending beneath the mouth of the hopper, means preventing the projection of the blanks beyond a point where the first blank of the series is in alignment with said track, a reciprocating pusher rod mounted upon said track and movable across the mouth of the hopper into engagement with the first blank of the series to move it laterally, and a resilient finger on 60 the pusher rod engaging said first blank. 65

12. A box forming machine including a bed, a horizontally arranged hopper mounted upon said bed and adapted to contain a series of vertically arranged blanks, means resiliently urging said blanks toward the open mouth of the hopper, a track disposed immediately beneath the open mouth of the hopper and extending laterally, a push rod forming a delivery device and slidingly mounted upon said track, means for reciprocating said push rod transversely to the axis of the hopper, and adjustable fingers extending in front of said hopper and having terminal portions extending inward toward the front of the hopper and in line with the outer face of the track. 70 75 80

13. A box forming machine including a bed, a horizontally arranged hopper mounted upon said bed and adapted to contain a series of vertically arranged blanks, means resiliently urging said blanks toward the open mouth of the hopper, a track disposed immediately beneath the open mouth of the hopper and extending laterally, a push rod forming a delivery device and slidingly mounted upon said track, means for reciprocating said push rod transversely to the axis of the hopper, and vertically adjustable fingers extending in front of said hopper and having terminal portions extending inward toward the front of the hopper and in line with the outer face of the track. 85 90 95

14. A box forming machine including in its organization a blank hopper having a discharge opening at one end and a pair of reciprocating glue applying brushes movable across the open end of the hopper. 100

15. A box forming machine including in its organization a blank hopper having a discharge opening at one end, a glue trough disposed below the hopper, and a pair of vertically reciprocating glue applying brushes movable across the opening of the hopper and into said trough. 105

16. A box forming machine including in its organization a horizontally disposed blank hopper having a discharge opening at one end, a guide extending upwardly from said discharge opening, a glue trough disposed below the discharge opening, a sliding member reciprocating in said guide, rods carried by said sliding member and normally dipping into the glue trough, and brushes carried on said rods. 110 115

17. A box forming machine including in its organization a horizontally disposed blank hopper having a discharge opening at one end, means for urging a series of vertically disposed blanks longitudinally along said hopper toward the discharge end, and a pair of spaced glue applying brushes movable across the opening of the hopper and into contact with the margins of the first blank of the series, and means for adjustably spacing said glue applying brushes. 120 125 130 135

18. A box forming machine including in its organization a bed, a hopper comprising oppositely disposed vertical walls, one of said walls being adjustable toward or from the other, one end of the hopper being open to form a discharge mouth, a plunger engaging with the first blank of a series of blanks disposed in said hopper and urging the blanks toward the open end of the hopper, and means mounted in front of the hopper for limiting the outward movement of the blanks, said means being adjustable in two directions whereby the means may be centered relative to different sized blanks, a track extending transversely across the hopper with its edge in alinement with the bottom of the hopper, and delivery devices reciprocable laterally past the mouth of the hopper for delivering the blanks one by one.
19. A box forming machine including a bed, a hopper having vertical side walls, said hopper being open at one end and adapted to contain a series of vertically disposed blanks, means urging the blanks toward the open mouth of the hopper, a track extending below the mouth of the hopper, means disposed in front of the mouth of the hopper limiting the outward movement of the blanks but permitting the first blank of the series to be disposed upon said track, a wall extending at right angles to the mouth of the hopper, a guide vertically adjustable upon said wall, and a reciprocating pusher rod mounted in said guide and movable past the mouth of the hopper and engageable with the first blank of the series to discharge it from the hopper.
20. A box forming machine including in its organization oppositely disposed hoppers each adapted to contain a series of vertically disposed blanks, the adjacent ends of said hoppers being open, blank delivery means in said hoppers for delivering the blanks one by one, blank feeding means reciprocating across the face of the hoppers, and reciprocating glue applying means, one of said hoppers with its corresponding feeding means, delivery means and glue applying means being adjustable toward or from the other hopper above said glue trough.
21. A box forming machine including in its organization opposed horizontally arranged blank hoppers opening at adjacent ends into a guideway, means disposed in said hoppers for forcing the end blanks contained therein one by one into said guideway, and reciprocating feed rods disposed within the guideway and moving past the ends of the hoppers and adapted to engage the blanks fed from said hoppers and shift them along said guideway.
22. A box forming machine including in its organization opposed hoppers opening at adjacent ends upon a guideway, tracks ex-
- tending along said guideway beneath the open ends of the hoppers, and parallel spaced reciprocating feed rods movable across the open ends of the hoppers upon said tracks and adapted to engage the blanks forced from said hoppers and shift them along the guideway.
23. A box forming machine including in its organization oppositely disposed blank hoppers, each adapted to contain a series of blanks arranged in a vertical position, tracks extending beneath the open ends of the hoppers, guide walls, one for each hopper and defining said guideway, and feed rods having sliding engagement with the guide walls and moving across the open ends of the hoppers, and means for reciprocating said feed rods simultaneously.
24. In a box forming machine, a table, a guideway, oppositely disposed blank hoppers arranged on either side of the guideway and opening at the adjacent ends upon the guideway, each hopper being adapted to contain a series of vertically disposed blanks, means for urging said blanks one by one out of the hoppers, guide walls extending on either side of the guideway and being longitudinally grooved, and feed rods each formed upon its outer face with an outwardly projecting tongue, the tongue engaging in the said guideway walls and each tongue being adapted to engage the end of the blank projecting from the mouth of its corresponding hopper, and means for simultaneously reciprocating said feed rods.
25. A box forming machine including in its organization oppositely disposed hoppers opening at their adjacent ends upon a guideway, each hopper being adapted to contain a series of vertically disposed blanks, a track extending transversely beneath each hopper, parallel guide walls extending from the hoppers and spaced from each other, each guide wall being formed with a longitudinally extending groove, and reciprocating feed bars having tongues operating in the grooves of the guide walls, said tongues extending only a portion of the length of the feed rods, and means for reciprocating the feed rods in one direction to retract the feed rods to such position that the ends of the tongues will engage the blanks projecting from the hoppers and reciprocating the feed rods in the other direction to shift said blanks from the hoppers.
26. A box forming machine including in its organization oppositely disposed end blank hoppers, transversely operating feed rods engaging said end blanks to move them into a box assembling space, a guideway leading to said box assembling space, oppositely disposed side blank hoppers arranged one on each side of said guideway, means for urging the side blanks contained therein one by one into said guideway, and recipro-

- cating feed rods moving past the openings of the hoppers and adapted to engage said side blanks and shift them into the box assembling space.
- 5 27. A box forming machine including in its organization a bed, horizontally disposed, parallel end blank hoppers spaced from each other and adapted to contain a series of vertically disposed end blanks, 70
- 10 means reciprocating transversely to the axes of the hoppers for delivering said end blanks to an assembling space, a guideway extending parallel to the axes of the end blank hoppers and extending from said assembling 75
- 15 space, said side blank hoppers arranged one on each side of the guideway and oppositely disposed to each other, each hopper opening upon the guideway, reciprocating delivering means moving along the guideway and 80
- 20 in front of said last named hoppers for delivering said side blanks from the side blank hoppers to the assembling space, an abutment shiftable into position behind one of the end blanks at one end of the assembling 85
- 25 space, and a hammer disposed at the other end of the assembling space opposite said abutment and movable toward and into engagement with the adjacent end blank to compress the blanks between the abutment 90
- 30 and the hammer.
28. In a box forming machine, a bed, oppositely disposed end blank hoppers spaced from each other, the adjacent ends of the hoppers being open, a longitudinally shiftable hammer mounted upon the bed and extending parallel to the end blank hoppers, a track extending below one of the end blank hoppers and extending to a position immediately in front of said hammer, a track parallel to the first named track and extending beneath the other end blank hopper and extending to a position opposite the hammer but spaced therefrom, lateral supports spaced from each other and disposed between said tracks, a guideway extending into the space between said supports, oppositely disposed side blank hoppers arranged on either side of said guideway and opening thereon, an abutment shiftable from a position at one side of said guideway to a position across said guideway and opposite the hammer and disposed adjacent to the second named track, means for delivering a blank from the first named hopper into position in front of said hammer, means for delivering said blanks from the side blank hoppers into a position between said supports, means for delivering an end blank from the second named end blank hopper into position opposite the first end blank, means for shifting the abutment into operative position against the last named end blank, means for shifting the hammer to press the end blanks into engagement with the side blanks, means for laterally shifting the completed box, and 100
- 35 means for ejecting the box.
30. In a box forming machine, a bed, oppositely disposed end blank hoppers mounted upon the bed and opening toward each other, tracks extending beneath the end blank hoppers and terminating at a box assembling space, side supporting means disposed on each side of the box assembling space, a hammer disposed at one end of the box assembling space, resilient means carried by the hammer for holding the box end upon the track at one end of the assembling space, a guideway leading to the assembling space and extending parallel to the axes of the end blank hoppers, side blank hoppers arranged on either side of the guideway, tracks extending beneath the side blank hoppers and extending along said guideway and terminating at the assembling space, an abutment laterally movable into and out of 110
- 40 position at the end of said assembling space opposite the hammer, means for shifting an end blank into position in front of said hammer, means for shifting the said blanks from said side blank hoppers to positions 115
- 45 on either side of the assembling space and against said supports, means for shifting the second end blank into position at the end of the assembling space opposite the first end blank, means for shifting the abutment into 120
- 50 position at the end of said assembling space opposite the hammer, means for shifting an end blank into position in front of said hammer, means for shifting the said blanks from said side blank hoppers to positions 125
- 55 on either side of the assembling space and against said supports, means for shifting the second end blank into position at the end of the assembling space opposite the first end blank, means for shifting the abutment into 130
- 60 position at the end of said assembling space opposite the hammer, means for shifting an end blank into position in front of said hammer, means for shifting the said blanks from said side blank hoppers to positions 135
- 65 on either side of the assembling space and against said supports, means for shifting the second end blank into position at the end of the assembling space opposite the first end blank, means for shifting the abutment into

position against said last named end blank, and means for longitudinally reciprocating the hammer to force the end blanks into engagement with the side blanks.

- 5 31. In a box forming machine, a bed, a laterally shiftable wall mounted upon the bed and forming one side of a box assembling space, a support opposite said wall, means for feeding side blanks into said box
 10 assembling space, means for feeding end blanks into said box assembling space, means for forcing said end blanks into engagement with the side blanks to complete the box, means carried by said wall yieldingly engaging the completed box, means for shifting said wall laterally to carry the completed box away from the box assembling space, and subsequently operating ejecting means engaging said box after the wall is shifted.
 15 32. A box forming machine including in its organization a bed, a side blank support mounted on the bed, a laterally reciprocating slide on the bed, a side blank supporting wall carried by the slide and opposed to the
 20 first named support and movable with the slide toward and away from the support, yielding blank clamping means carried by the wall, a discharge guideway, means for assembling end and side blanks between said
 25 blank supporting means, means for shifting said slide to carry the supporting wall into alinement with one wall of the discharge guideway, and means for disengaging the box from the wall and ejecting it along said
 30 35 guideway.

33. A box forming machine including in its organization a bed, spaced side blank supports mounted on the bed, a laterally reciprocating slide on the bed, a side blank supporting wall carried by the slide and opposed to the first named supports and movable with the slide toward and away from said supports, yielding blank clamping means carried by the supporting wall and
 40 including a ledge disposed at the bottom of the wall and a resilient clamp disposed at the top of the wall, a discharge guideway, means for assembling end and side blanks between said supports and the supporting wall, means for shifting said slide to carry the supporting wall into alinement with the outer wall of the discharge guideway, and a reciprocating finger movable into engagement with the box and ejecting the box
 45 50 55 along said discharge guideway.

34. A box forming machine including a bed, side blank supports mounted on the bed, each of said supports having a supporting ledge, a laterally reciprocating slide on the bed, a side blank supporting block carried by the slide and opposed to the first named support, said block being formed with a projecting ledge on its inner face, a resilient clamp mounted upon the block above said
 60 65 66 ledge, said supporting wall being movable

with the slide toward and away from the first named side blank supports, means for assembling end and side blanks between said supports, an abutment movable into position behind one of said end blanks, a hammer 70 shiftable longitudinally to force said end blanks into engagement with the side blanks, a discharge guideway located to one side of but parallel to the hammer, means for shifting said slide to carry the supporting block 75 into alinement with the outer wall of said guideway, and means for disengaging the box from said supporting block and ejecting the box along said guideway.

35. A box forming machine including in 80 its organization a plurality of side blank supports mounted in alinement with each other, certain of said supports being adjustable toward or from the other supports, each of said supports being formed with a ledge 85 and all of said supports being adapted to support one side blank of a box, a side blank supporting wall opposed to said first named supports and formed with a ledge near its lower edge, a yielding clamp carried by said supporting wall above said ledge, a slide upon which the supporting wall is mounted for longitudinal adjustment, said slide being laterally movable, means for assembling box 90 ends and sides between the said supports 95 and the supporting wall, means for pressing the box ends into engagement with the sides, means for laterally shifting the slide to carry the completed box laterally, and means for disengaging the box from the supporting 100 block and ejecting the box.

36. A box forming machine including in its organization oppositely disposed, horizontally arranged end hoppers opening at their adjacent ends, side blank supports 105 mounted in spaced relation to each other, means for shifting end blanks from said hoppers into position at opposite ends of the space defined by said supports, a slotted guideway leading to the space between said 110 supports, side blank hoppers opening upon said guideway, means operating in said guideway for shifting side blanks from said hoppers into position against said supports, and means operating in said guideway for shifting bottom blanks along said guideway 115 and into position between said side blanks.

37. A box forming machine including in its organization side blank supporting members defining an assembling space, a guideway leading to said assembling space, means for delivering an end blank into position at one end of said assembling space, means for delivering side blanks into position on each side of said assembling space and against 120 said supports, means for delivering a bottom blank into position between said side blanks, and means for delivering an end blank into position between said side supports, and at the end opposite said first 125 130

named end blank, and means for forcing the end blanks into engagement with the side blanks.

38. A box forming machine including in its organization a bed, oppositely disposed, parallel, spaced side blank supporting members mounted upon said bed and defining the sides of a box assembling space, a hammer disposed at one end of said space and movable toward or from the ends of the side blank supporting members, a guideway in line with said box assembling space, means for delivering end blanks into position at opposite ends of the assembling space, means for delivering the side blanks along said guideway into position against the side blank supporting members, a bottom blank delivering member moving longitudinally along said guideway and delivering bottom blanks between said side blanks, and means for forcing the end blanks into engagement with the side blanks.

39. A box forming machine including a bed, spaced, parallel side blank supports mounted on said bed and defining the sides of a box assembling space, a hammer defining one end of said box assembling space and movable toward or from the middle thereof, a guideway leading to said box assembling space, means for delivering side blanks along said guideway and into position on either side of the box assembling space and against said supports, means for delivering an end blank into position against the face of the hammer, an endless traveler movable along the guideway and having projecting members adapted to engage horizontally disposed bottom blanks and shift the same into position between said side blanks, means for delivering a second end blank into position at the end of the box assembling space opposite the hammer, and means for operating said hammer to force the end blanks into engagement with the side blanks.

40. A box forming machine including in its organization a horizontally arranged hopper having side walls and open at one end, said hopper being adapted to carry a series of vertical blanks, means urging said blanks toward the opening of the hopper, a vertically disposed wall extending to one side and above the opening of the hopper, said wall being provided with a vertical guide immediately above the opening of the hopper and a laterally extending guide in alignment with the opening of the hopper, said guide being vertically adjustable, a sliding rod movable in said guide across the opening of the hopper and adapted to engage with the first blank of a series of blanks supported in the hopper, and vertically adjustable fingers mounted upon the vertical guide and extending down in front of the hopper and having an inwardly

turned end adapted to engage with and limit the outward movement of the first blank of the series.

41. A box machine including a bed, a glue trough carried in said bed, oppositely disposed, horizontally arranged end blank hoppers mounted on said bed and having their adjacent ends open, transversely sliding rods moving past the open ends of the hoppers and adapted to engage the first blank of the series of blanks supported in the corresponding hopper, a shaft extending longitudinally above the bed, cams mounted on the shaft, levers connected at their lower ends to said feed rods and connecting rods, pivotally connected at their upper ends to said levers and adapted to be engaged by the cams.

42. In a box forming machine, a bed, a laterally shiftable wall mounted upon the bed and forming one side of a box assembling space, a support opposite said wall, means for feeding side blanks into said box assembling space, means for feeding end blanks into said box assembling space, means for forcing said end blanks into engagement with the side blanks to complete the box, a box support extending from the lower end of said wall across the lower portion of the box assembling space and having an upwardly turned end and adapted to engage a completed box with said wall, and means for shifting the wall laterally to carry the completed box away from the box assembling space.

43. In a box forming machine, a laterally shiftable wall forming one side of a box assembling space, the inner face of the wall being provided with a ledge disposed near the bottom thereof, supports opposed to the wall and formed with box supporting ledges, and means for engaging a completed box with said wall comprising a wire extending outward from the lower end of the said wall below the ledge and having an upturned end normally projecting into the space between the opposed supports, and means for shifting said wall laterally in a direction away from said supports to carry the completed box away from the box assembling space.

44. In a box forming machine, a bed, a side blank support mounted on the bed, a slide reciprocating laterally on the bed, a side blank supporting wall carried by the slide and opposed to the first named support and movable with the slide toward and away from the support, yielding blank clamping means carried upon the face of the wall, a member projecting from the face of the wall and having an upturned end adapted to engage a completed box and hold it to the wall, a discharge guideway, means for assembling end and side blanks between said blank supporting means, means for

- shifting said slide to carry said supporting wall into alinement with one wall of the discharge guideway, and means for longitudinally shifting the box along the wall 5 and ejecting it into said guideway.
45. A box forming machine including in its organization side and end blank hoppers, means for assembling side and end blanks discharged from said hoppers, means for 10 forcing said side and end blanks into engagement with each other, a discharge guideway comprising oppositely disposed parallel walls, means for shifting the completed box into a position of alinement with 15 said guideway, and a member moving in a curved path in the direction of said guideway and adapted to engage the box and shift it into said guideway.
46. A box forming machine including in 20 its organization side and end blank hoppers, means for carrying said side and end blanks from said hoppers and box forming space, means for engaging the side and end blanks with each other, a discharge guideway extending parallel to the box forming space, means for shifting the completed box from the box forming space into a position of alinement with said guideway, and a member pivoted in line with said guideway for 25 movement parallel thereto and adapted to engage the completed box and shift it into said discharge guideway.
47. A box forming machine including in 30 its organization side and end hoppers, each 35 having upwardly extending side walls, said walls being adjustable toward and from each other, the end hoppers being adjustable toward or from each other, means for feeding end blanks and side blanks from said 40 hoppers, means for delivering the side and end blanks so fed to an assembling space, means for forcing the end blanks into engagement with the side blanks to form a completed box, a discharge guideway having 45 vertical walls adjustable toward or from each other, said guideway extending parallel to the length of the assembling space, means for shifting the assembled box from the assembling space to a position in front of said
- guideway, and means for ejecting the box 50 into the guideway.
48. A box forming machine including in its organization oppositely disposed end and blank hoppers, each adjustable for width and each adjustable toward or from 55 each other, oppositely disposed side blank hoppers, each adjustable for width, glue applying devices for each end blank hopper comprising parallel brush supporting rods, said rods being adjustable toward or from 60 each other, means for delivering end blanks to a box assembling space, means for delivering the side blanks thereto, means for forcing the end blanks into engagement with the side blanks, a delivery guideway 65 having vertically disposed side walls adjustable toward or from each other, and means for shifting the completed box from the box assembling space into said guideway. 70
49. In a box forming machine, a glue trough, blank hoppers disposed on each side of the glue trough, means for adjusting said hoppers nearer to or farther from each other over said glue trough, and reciprocating 75 glue applying devices moving across the open mouths of the hopper.
50. In a box forming machine, oppositely disposed side blank hoppers opening upon a guideway leading to a box assembling space, 80 means moving along said guideway for delivering side blanks to the box assembling space, and oppositely disposed end blank hoppers extending at right angles to the side blank hoppers and in line with opposite 85 ends of the box assembling space, all of said hoppers being arranged in a horizontal plane and having vertical side walls and being adapted to contain a plurality of blanks in a vertical position, and means for 90 shifting the end blanks and side blanks to the box assembling space.

In testimony whereof I affix my signature in presence of two witnesses.

MICHAEL QUINLAN. [L.S.]
